Inventor:

Le Roy D. Way

UNITED STATES PATENT OFFICE.

LE ROY D. WAY, OF RUGBY, NORTH DAKOTA.

SAFETY WINDOW-CATCH.

No. 880,610.

Specification of Letters Patent.

Patented March 3, 1908.

Application filed May 6, 1907. Serial No. 372,273.

To all whom it may concern:

Be it known that I, LE ROY D. WAY, a citizen of the United States, residing at Rugby, in the county of Pierce and State of North Dakota, and whose post-office address is Rugby, North Dakota, have invented new and useful Improvements in Safety Window-Catches, of which the following is a specification.

10 My invention is a safety window catch, which may be applied to and used on any window where the sash slides up and down.

The object of my invention is to securely hold a window sash at any point placed, and 15 to permit it to slide up and down when desired.

In the accompanying drawings, Figure 1, is a face view of my invention, the top plate removed. Fig. 2, is a rear view. Fig. 3, is a 20 cross sectional view, on the line 3, 3, of Fig. 1, looking from the front end thereof. Fig. 4, is a longitudinal sectional view, on the line 4, 4, of Fig. 1.

Similar letters refer to similar parts 25 throughout the several views.

In describing my invention I read the drawings from left to right.

My invention is described as follows:

In the accompanying drawings, the letter 30 *a*, represents eccentric wheels pivoted to the face of the bottom plate *a*¹, near the front end thereof. The periphery of each wheel is grooved as shown at *b*¹, and is covered by a rubber band *b*; *c*, represents rivets in which 35 said eccentric wheels turn; *d*, represents elbow levers, pivoted to the plate at their elbows by means of pivots *e*, their free ends extending rearwardly through a slot *a*², in the flange *a*³, of said bottom plate *a*¹. The 40 said eccentric wheels, each has extending from its periphery a short arm *a*⁴, and pivoted to each of the said short arms are the front ends of links *f*; the rear ends of these links are pivoted to the extreme forward 45 ends of the fore-arms *d*¹, of said elbow levers *d*. Secured to said links, near their rear ends, is a coiled spring *g*, in such position as to pull the said rear ends of said links together, and thereby open the rear ends of said elbow 50 levers, and at the same time throw said short arms *a*⁴, of said eccentric wheels *a*, forward, and thereby throw said wheels against the

window casing, and thus hold the sash firmly in the position placed.

When I wish to move the sash up or down, 55 I press the free ends of the elbow levers together which has the effect, by means of the mechanism just described, of withdrawing the said wheels from said sash. The said plate *a*¹, is provided at its center with a 60 threaded elevation *h*, and by means of a screw *l*, the top plate *a*⁵, is fastened to the said bottom plate *a*¹. The device is secured to the sash by means of screws, which pass through screw holes *i*, in the top and bottom 65 plates.

Although I have specifically described the combination, construction and arrangement of the several parts of my invention I do not confine myself particularly to such 70 specific combination, construction and arrangement, as I claim the right to make such changes and modification therein as may clearly fall within the scope of my invention, and which may be resorted to without departing from the spirit, or sacrificing 75 any of my patentable rights therein.

Having described my invention, what I claim as new and desire to secure by Letters Patent, is:—

A safety window catch, consisting of a bottom plate *a*¹, provided with a flange *a*³, having a slot *a*², a central threaded elevation *h*, and screw holes *i*; eccentric wheels *a*, having their periphery grooved, pivoted to 85 the face of said plate near its front end; rubber bands *b*, covering the peripheries of said wheels; elbow levers *d*, pivoted to said plate near its rear end; short arms *a*⁴, extending from said wheels *a*; links *f*, their front ends 90 pivoted to the free ends of said short arms, their rear ends to the extreme forward ends of the fore-arms of said elbow levers; a coiled spring secured to said links near their rear ends, in position to hold said wheels 95 against the window casing, and a top plate *a*⁵, secured to said bottom plate by means of a screw *l*, substantially as shown and described and for the purposes set forth.

LE ROY D. WAY.
